UNITED STATES PATENT OFFICE.

PHILIP T. DODGE, OF WASHINGTON, DISTRICT OF COLUMBIA, ASSIGNOR TO MERGEN-
THALER LINOTYPE COMPANY, A CORPORATION OF NEW YORK.

TYPOGRAPHICAL COMPOSING-MACHINE.

1,074,933.

Specification of Letters Patent.

Patented Oct. 7, 1913.

Application filed January 2, 1912. Serial No. 668,889.

To all whom it may concern:

Be it known that I, PHILIP T. DODGE, a citizen of the United States, and a resident of Washington, in the District of Columbia, have invented a new and useful Improvement in Typographical Composing-Machines, of which the following is a specification.

My invention relates to typographical composing machines, such as linotype machines of the general organization represented in Letters Patent of the United States, No. 436,532, to O. Mergenthaler, wherein circulating matrices are released from a magazine in the order in which their characters are to appear in print and then assembled in line together with expanding spacers, the composed line transferred to the face of a mold, the mold filled with molten metal to form a slug or linotype against the matrices which produce the type characters thereon, and the matrices thereafter elevated and returned through a distributing mechanism to the magazine or magazines from which they started. More particularly the invention relates to that class of typographical composing machines in which a series of magazines is employed and which may be shifted so as to bring any selected one into operative relation to the assembling devices, as shown in my Letters Patent of the United States, No. 800,556. In connection with movable magazines of the kind already referred to, I propose to employ a movable throat or means for conducting the type or matrices from the distributing mechanism to the magazine in operative position, and in the specific form illustrated and described, I have shown the throat as pivotally mounted, and have also illustrated means whereby when the magazines are moved in one direction to bring any one into operative position, the throat will be moved in the opposite direction so as to register with the selected magazine. The magazines are also shown as provided with escapements connected thereto and movable with the magazines when the latter are shifted, and in order to permit their free movement without interfering with, or being forced to adjust, the escapement operating means or gears, I dispose the latter out of the path of the movable magazines and in a plane apart from the escapements, and so

construct and arrange the said means that their actuation effects the double function, first of moving them into register with the respective escapements, and secondly, of operating the escapements to release the corresponding type or matrices from the magazine. These and other improvements are illustrated in the accompanying drawings in preferred form by way of example, and as applied to a linotype machine, but obviously many changes and variations may be made therein and in their mode of application without departure from the scope of the invention; and generally speaking I desire it to be understood that I do not limit myself to any specific form or embodiment, except in so far as such limitations are specified in the claims.

Referring to the drawings: Figure 1 is a rear view of part of a linotype machine having my invention applied thereto; Fig. 2 is a transverse vertical section thereof; Fig. 3 is a similar view of the upper portion of the machine, showing the movable throat in a different position; Fig. 4 is a similar view of the lower portion of a magazine, etc., showing the escapement operating means in a different position; Fig. 5 is a sectional detail view taken substantially on the line 5-5 in Fig. 1; Fig. 6 is a detail view on an enlarged scale of the means for shifting the magazines; and Fig. 7 is a detail view showing a modified arrangement of the device for shifting the escapement operating means.

Referring to Figs. 1, 2 and 3, the distributing mechanism is or may be of the usual type, as set forth in the Mergenthaler patent previously referred to, or in the ordinary commercial linotype machine, and comprises the distributor bar or rail A, along which the matrices X are conveyed by the distributor screws A¹, until they are released therefrom and pass through the throat or conducting means B into the appropriate channels of the magazine in use. In the present instance I have shown two magazines, C and C¹, although any desired or convenient number thereof may be employed, and in order to permit them to be shifted so as to bring the selected one into operative position, I have mounted them in a frame C², pivotally mounted on the framework at C³, much in the same manner as set forth in my Letters Patent, No. 800,556, 110

previously mentioned. It will be obvious that the frame C^6 may be swung about its pivot C^2 so as to bring either magazine, C or C^1 , into operative relation to the vertically channeled front or guide plate D , through which the released matrices descend to the further devices by which they are assembled in line, as in the ordinary linotype machine. The means for effecting the shifting 10 of the magazines are specifically different from those illustrated in my said patent, and comprise in the present instance (see Fig. 6) a hand-lever E mounted upon a rock shaft F , which latter carries arms F^1 , preferably provided with rollers in contact with the magazine shift frame C^6 . The manual operation of the lever E effects the rotation of the shaft F and arms F^1 carried thereby, so as to move the magazine frame C^6 about 15 its pivot C^2 and to bring either magazine into operative relation to the assembling devices. The arm E is provided with a spring-pressed locking device E^1 , adapted to engage with notches in the plate E^2 , whereby the selected magazine is locked in position. I have also arranged the throat B so that it may be moved about a pivotal support B^1 in order that it may be caused to register with the magazine in use, and to permit the matrices X to be delivered thereto as they pass 20 from the distributor rail or bar A . This auxiliary movement of the throat is necessitated by the fact that the pivotal support C^2 of the frame C^6 is located at or near the upper end thereof, and consequently, when it is swung about it, the shifting of the magazines is effected with a very slight relative movement of their upper ends. In other words, when the magazines are piv- 25 ally moved from one position to another, the effect upon their upper ends is little more than to change their angular relations, and therefore it is necessary that the throat B should be shifted from its former opera- 30 tive position to register with the other magazine. It also follows from this arrangement that when the lower ends of the magazines are thus shifted, the throat must be moved in the opposite direction to cause it to register 35 properly. It should also be noted that the pivotal support B^1 of the throat B is located at or near the upper end thereof and in im- 40 mediate proximity to the distributing mechanism, so that when the throat is shifted, its upper end is not moved sufficiently to affect 45 its operative relation to the distributing mechanism, but will always be in position to receive the matrices therefrom.

In order to effect the movement of the 50 throat conjointly with that of the magazines, and in the opposite direction thereto, the arm G is mounted upon the rock shaft F and connected by a link G^1 to the elbow lever G^2 , which in turn is connected by the 55 link G^3 to the throat. When the hand-lever

E is manipulated, not only will the magazines be shifted in the manner previously described, but through the connections G , G^1 , G^2 and G^3 , the throat will be moved in the opposite direction. This mode of operation is clearly disclosed in Figs. 2 and 3. In Fig. 2 the upper magazine C is shown by full-lines in operative relation to the face plate D and the throat B in proper position to deliver the matrices from the distributing 70 mechanism to the said magazine. When the handle E is moved from its full-line to its dotted-line position, the magazines are shifted to their dotted-line position, thereby bringing the magazine C^1 into operative relation to the face plate, and at the same time the throat B is swung from its full-line position to its dotted-line position in order to register therewith. This latter operative relation of the throat B to the magazine C^1 is 75 shown in full lines in Fig. 3.

In order to permit the movements of the throat and magazines relatively to each other and in opposite directions, the upper ends of the magazines are suitably formed 80 and curved as shown in the drawings; and still further to prevent the possibility of their contacting or binding during such movements, I provide the shifting means with a lost motion device, as illustrated more 85 particularly in Fig. 5. The hubs of the arms F^1 are loosely mounted upon the rock shaft F and are formed with slots E^2 , through which project screws or studs F^3 firmly connected to the rock shaft F . Due 90 to this arrangement, when the hand-lever E is operated, its first effect will be to move the arm G , rigidly mounted thereon, and thus to initiate the movement of the throat B before the magazines are affected. The 95 magazine shifting arms F^1 will not be operatively moved until the screws F^3 on the rock shaft F engage with the ends of the slots E^2 . In this manner and because of the commencement of the movement of the 100 throat before that of the magazine, I obviate any liability to the interference of the lower end of the throat with the upper ends 105 of the magazine.

Each of the magazines is provided with escapement devices H , which may be of any desired or known form, although in the drawings they are shown as of the one-piece variety familiar in the art. While there is a plurality of series of such escapements, a single series of operating means or reeds is employed in connection therewith, and these operating means or reeds are arranged in a plane outside of and apart from the escapements, and out of the path of the magazines, 110 so that the latter may be shifted without special manipulation of the reeds to clear the magazines, as is sometimes necessary.

The reeds or escapement operating means are or may be actuated longitudinally in the 115

customary manner, as disclosed for instance in Letters Patent of the United States to O. Mergenthaler, No. 531,236, or to P. T. Dodge, No. 530,931, and consequently such actuating devices are not disclosed herein. Referring to Fig. 2, the reeds are formed in two sections, an upper section J and a lower section J¹, the two parts being connected by a joint which permits a slight lateral movement of the upper section J. Loosely connected to each section J is a link J², which is pivotally mounted in the framework. In their ordinary condition the sections J occupy the position shown in Fig. 2, in a plane apart from the escapements H and out of the path of the shiftable magazines. Due to this arrangement and position, it will be obvious that the magazines are at all times free to be shifted without interference with the reeds. When the reeds are longitudinally actuated in the manner previously referred to, and due to the connected pivoted links J², the sections J will partake of two movements, first a lateral one which brings the section J under and in operative relation to the escapement H, and second a continued longitudinal movement which operates the escapement in the usual manner, as shown in Fig. 4. When the reeds are returned in the opposite direction they will again assume their normal position as shown in Fig. 2.

In Fig. 7 I have shown an alternative construction, wherein the reeds J¹⁰ are made in a single piece, and their lateral movement to bring them into operative relation to the escapements is secured by a laterally shiftable guide J¹¹, which may be actuated in any desired manner.

As previously stated, I have shown my invention in preferred form by way of example, but obviously there will be many changes and variations therein and in their mode of application, which will suggest themselves to those skilled in the art and still be comprised within its spirit.

Having thus described my invention, its construction and mode of operation, what I claim and desire to secure by Letters Patent of the United States is as follows:

1. In a typographical composing machine, the combination of distributing mechanism, assembling devices, a plurality of magazines movable to bring a selected one into operative relation to the assembling devices, and an independent single throat moved conjointly with the magazines to connect the distributing mechanism with the magazine in operative position.

2. In a typographical composing machine, the combination of distributing mechanism, assembling devices, a plurality of magazines movable to bring a selected one into operative relation to the assembling devices, and an independent throat movable to connect the

distributing mechanism with the magazine in operative position, together with means for moving the magazines and the throat conjointly.

3. In a typographical composing machine, the combination of distributing mechanism, assembling devices, a plurality of magazines movable in one direction to bring a selected one into operative relation to the assembling devices, and a single throat automatically and conjointly moved in the opposite direction to connect the distributing mechanism with the magazine in operative position.

4. In a typographical composing machine, the combination of distributing mechanism, assembling devices, a pivotally mounted series of magazines movable to bring a selected one into operative relation to the assembling devices, and a single pivotally mounted throat moved conjointly with the magazines to connect the distributing mechanism with the magazine in operative position.

5. In a typographical composing machine, the combination of distributing mechanism, assembling devices, a pivotally mounted series of magazines movable in one direction to bring a selected one into operative relation to the assembling devices, and a pivotally mounted throat automatically and conjointly moved in the opposite direction to connect the distributing mechanism with the magazine in operative position.

6. In a typographical composing machine, the combination of distributing mechanism, assembling devices, a pivotally mounted series of magazines movable to bring a selected one into operative relation to the assembling devices, and a pivotally mounted throat movable to connect the distributing mechanism with the magazine in operative position, together with means for conjointly moving the series of magazines and the throat about their respective pivots.

7. In a typographical composing machine, the combination of distributing mechanism, assembling devices, a plurality of magazines movable to bring a selected one into operative relation to the assembling devices, and a throat movable to connect the distributing mechanism with the magazine in operative position, together with conjoint means for moving the magazines and the throat, the said means being constructed to permit the partial shifting of the throat slightly in advance of that of the magazines.

8. In a typographical composing machine, the combination of assembling devices, a plurality of magazines movable to bring any one into operative relation to the assembling devices, and a single throat for delivering matrices to the magazines, said throat being automatically positioned when the magazines are moved.

9. In a typographical composing machine,

- the combination of distributing mechanism, assembling devices, a plurality of magazines movable to bring a selected one into operative relation to the assembling devices, and 5 a single throat for conducting the type or matrices from the distributing mechanism to the magazine in operative position, the said throat being automatically positioned when the magazines are moved.
- 10 10. In a typographical composing machine, the combination of distributing mechanism, assembling devices, a plurality of magazines movable to bring a selected one into operative relation to the assembling devices, and 15 a throat moved conjointly with and relatively to the magazines to connect the distributing mechanism with the one in operative position.
11. In a typographical composing machine, the combination of a magazine, a series of escapements, and operating means for the said escapements normally out of operative relation thereto, the said means being capable of two different movements, 20 in one direction to bring them into such operative relation, and in another direction to operate the escapements, the former action being controlled by the latter.
12. In a typographical composing machine, the combination of a magazine, a series of escapements, and operating means for the said escapements normally out of 25
- operative relation thereto. the said means being capable of two different movements, laterally to bring them into such operative 35 relation, and longitudinally to operate the escapements, the former action being controlled by the latter.
13. In a typographical composing machine, the combination of a magazine, a series of escapements and a corresponding series of longitudinally movable reeds for operating the escapements, the said reeds being laterally removed from the escapements and being provided with means whereby they are 40 shifted laterally to engage therewith when longitudinally actuated.
14. In a typographical composing machine, the combination of a magazine, a series of escapements and a corresponding series of longitudinally movable reeds for operating the escapements, the said reeds being laterally removed from the escapements and being provided with pivoted links whereby they are shifted laterally to 45 engage the escapements when longitudinally actuated.

In testimony whereof I hereunto set my hand this 21st day of December, 1911, in the presence of two attesting witnesses.

PHILIP T. DODGE.
